CORE DRILL

John H. Howard, Huntington Park, and Alfred C. Catland, Alhambra, Calif., assignors to Globe Oil Tools Company, Los Nietos, Calif., a corporation of California

Application August 7, 1933, Serial No. 684,018

2 Claims. (Cl. 255—72)

This invention relates to a well drilling tool, and relates more particularly to a core drill for obtaining samples or cores of the earth formation. It is a general object of the invention to provide a simple, practical and particularly effective core drill.

It has been found desirable to mount the inner core receiving barrel of a rotary core drill in a manner so that it is free to remain stationary or not rotate with respect to the core during the drilling operation. In the core drills that have been introduced having "floating" inner barrels that may be held against rotation through contact with the core during the rotation of the drills, the inner barrels are usually rotatably supported from their upper ends. Rotatably supporting the inner barrel of a core drill from its upper end greatly complicates the construction, and necessitates the provision of guiding means and packing means at the lower end of the barrel to prevent circulation fluid from washing away the core. The core receiving inner barrels of the various classes of core drills that have been introduced have valves or other elements connected to their upper ends by screw threads and have their lower ends threadedly connected with the bit head or other support. The provision of screw threads on the inner barrel of a core drill requires that the barrel have comparatively heavy or thick walls. Heavy inner barrels are expensive, and materially reduce the diameter of the cores that may be taken by the drill. Further, "floating" inner barrels having thick walls are very heavy and are not readily held against rotation by engagement with the core, and often rotate with the drill.

Another object of the invention is to provide a core drill including a "floating" inner barrel having thin walls whereby it is operable to receive a core of maximum diameter and is extremely light in weight and inexpensive of manufacture.

Another object of the invention is to provide a core drill having an inner barrel for receiving the core that is entirely without screw threads so that it may have very thin walls. As the inner barrel of the drill provided by the present invention has no threads cut in it and does not have to be handled by tongs or other turning tools, it may have very thin walls.

Another object of the invention is to provide a core drill including a simplified and improved valve assembly for the inner barrel that is dependably and effectively removable attached to

the upper end of the barrel without the employment of screw threads.

Other objects and features of the invention will be better and fully understood from the following detailed description of a typical form and application of the invention, throughout which description reference is had to the accompanying drawing, in which:

Fig. 1 is a side elevation of the core drill provided by the present invention with certain parts broken away to appear in vertical cross section. Fig. 2 is an enlarged side elevation of the valve means embodied in the core drill with a portion broken away to appear in vertical cross section. Fig. 3 is a top or plan view of the valve illustrated in Fig. 2. Fig. 4 is an enlarged fragmentary detailed sectional view taken substantially as indicated by line 4—4 on Fig. 5. Fig. 5 is an enlarged horizontal detailed sectional view taken as indicated by line 5—5 on Fig. 1. Fig. 6 is an enlarged vertical detailed sectional view of the core catcher embodied in the drill.

The rotary core drill provided by the present invention includes generally, an outer barrel 10, a bit head 11 on the lower end of the outer barrel 10, an inner barrel 12 for receiving the core cut by the bit head, a core catcher 13, and a removable valve 14 on the upper end of the inner barrel 12.

The outer barrel 10 is an elongate tubular structure adapted to be attached to the lower end of a well drilling string. The outer barrel 10 includes a tubular main section 15 provided at its upper end with a sub 16 having a tapered screw threaded pin 17 for facilitating connection of the barrel with the drilling string. A sub 18 is threaded on the lower end of the section 15 and carries a bit head sub 19.

The bit head 11 is attached to the lower end of the sub 19 and is provided to make an annular cut in the earth formation. The bit head 11 includes a tubular shoe or body 20 having circumferentially spaced cutting blades. Each of the cutting blades includes a pilot portion 21 and a reaming portion 22. The pilot portions 21 of the cutting blades extend downwardly directly below the lower end of the bit head body 20 and cut a comparatively narrow annular channel in the formation. The reaming portions 22 of the cutting blades project substantially radially from the bit head body and operate to cut or enlarge the bore to size. The cutting blades formed as just described prevent excessive washing away of the core. The bit head shoe or body 20 is provided

at its upper end with a screw threaded socket 23 for receiving the pin on the lower end of the sub 19 and the central opening 24 in the body 20 is operable to pass the core cut by the blade portions 21. An annular recess 25 is provided in the wall of the opening 24 at the lower end of the socket 23. The recess 25 rotatably carries the lower end of the inner barrel 12 and the core catcher 13, as will be subsequently described. Two vertically spaced upwardly facing shoulders 26 and 27 are provided on the walls of the recess 25. The bottom or lower end 28 of the recess 25 constitutes a third upwardly facing shoulder in the bit head body 20. The intermediate shoulder 15 27 is flat and is inclined downwardly and inwardly.

The inner barrel 12 is arranged longitudinally in the outer barrel 10 and is provided to receive the core cut by the bit head 11. It is an important feature of the present invention that the inner barrel 12 is rotatably supported in the bit head body 20 in a manner so that it may be held against rotation through contact with the core during rotation of the drill. The inner barrel 12 is an elongate tubular member extending from the recess 25 in the bit head to a point adjacent the sub 16. The lower end of the inner barrel 12 is open to receive the core while the upper end of the barrel 12 is closed by the valve means 14. In accordance with the present invention, the inner barrel 12 is not threaded at any point and therefore may have comparatively thin walls, as its walls do not have to carry tapered threads and do not have to be sufficiently rigid to withstand handling by wrenches, tongs, or other turning tools. It will be obvious that the inner barrel 12 having thin side walls allows the drill to be proportioned to cut and receive a core of maximum diameter with respect to the external diameter of the drill. Further, the thin walled inner barrel 12 is light in weight and inexpensive. The inner barrel 12 may be in the nature of a length of tubing of uniform diameter.

A ring or enlargement 29 is provided on the lower end of the inner barrel 12 to cooperate with the bit head body 20. The enlargement 29 is preferably welded to the barrel 12 and surrounds the lower end portion of the barrel. The enlargement 29 projects downwardly from the lower end of the inner barrel 12 in the upper portion of the recess 25 and its lower end is adapted to rotatably bear on the shoulder 26 to support the inner barrel 12 on the bit head body 20. Effective bearing means is provided for transmitting upward thrusts from the inner barrel 11 to the sub 19 in the event engagement with the core holds the inner barrel 12 up in the drill. A hardened bushing ring 30 is pressed in an annular recess 31 in the lower end of the sub 19. The upper portion of the barrel enlargement 29 extends into the bushing ring 30 and a bushing ring 32 is provided on the enlargement 29 to rotatably bear against the lower end of the ring 30. An internal annular recess 33 is provided in the lower end portion of the inner barrel enlargement 29 to carry or receive the upper part of the core catcher 13. It is to be particularly noted that the inner barrel 12 is rotatably carried entirely within the body 20 of the bit head 11. The means for rotatably supporting the inner barrel 12 is more fully described and claimed in our divisional application for Letters Patent entitled "Core drill", Serial Number 709,460, filed February 2, 1934.

The improved core catcher 13 is rotatably mounted in the bit head 11 so that it may be held

against rotation relative to the core. The core catcher 13 includes an annular body rotatably mounted in the recess 25 between the shoulder 28 and the upper end of the recess 33. The body of the core catcher 13 includes two rings, an outer ring 35 and an inner ring 36. The rings 35 and 36 are telescoped one within the other and have inclined bearing or cooperating faces 37. The opening 38 in the core catcher body is in vertical register and alignment with the opening 24 of the bit head and is operable to readily pass the core. Circumferentially spaced vertical slots 39 are provided in the inner ring 35 of the core catcher and vertical slots 40 are provided in the lower end of the outer ring 35 in vertical alignment with the slots 39. Core engaging and supporting dogs 41 are pivotally mounted in the slots 39 and protrude outwardly through the slots 40.

The invention provides novel means for pivotally supporting the core engaging dogs 41. Pins 20 42 extend through transverse openings in the dogs 41 and project from opposite sides of the dogs to extend into a groove 43 in the periphery of the inner body ring 36. The groove 43 is annular and is partially circular or cylindrical in cross section. The projecting ends of the dog supporting pins 42 are flattened as at 47 and cooperate with the walls of the groove 43 to positively prevent rotation of the pins. The rings 35 and 36 of the core catcher body are securely connected 30 together in a manner to prevent shifting or displacement of the dog carrying pins 42. Rivets 44 extend through radial openings in the rings 35 and 36 to dependably connect the rings. The rivets 44 are preferably positioned adjacent the 35 opposite ends of the dog carrying pins 42 to effectively prevent shifting of the pins. When it becomes desirable or necessary to replace the dogs 41, the rivets 44 may be drilled out to permit the disconnection of the rings 35 and 36, thereby allowing the removal of the pins 42 and dogs 41. While we have shown the rings 35 and 36 connected together by rivets 44, it is to be understood that these elements may be connected by screws or other equivalent means without departing from 40 the principles of the invention.

The dogs 41 of the core catcher are adapted to project into the core passing opening 38 of the core catcher body to engage and support the core. The undersides 45 of the dogs 41 are inclined upwardly and inwardly and the dogs are provided with sharp outer edges 46. The exposed portions of the inclined shoulder 37 of the outer ring 36, at the slots 39, allow the dogs 41 to pivot upwardly and outwardly to positions entirely clear of the core passing opening 38. It is a feature of the present invention that the active or core engaging inner portions of the dogs 41 are of different lengths. One or more comparatively short dogs 41^a are provided to support and retain cores of 50 hard earth formations. The dogs 41^a, in being comparatively short, have effective angles of attack or engagement so that it is practically impossible for a hard core of any appreciable diameter to slip through the core catcher when the 55 drill is raised. One or more dogs 41^b of medium length are provided on the catcher for supporting and retaining cores of soft formation which are quite frequently undersized in diameter. The dogs 41^b of medium length are operable to effectively grip and support cores that the smaller dogs 41^a are not capable of properly contacting. One or more long dogs 41^c are provided in the 60 catcher for supporting and catching cores which are badly broken or shattered. The longer dogs 70 75

41^c are operable to prevent badly broken cores from sifting or passing through the core catcher as the drill is raised. In the particular arrangement and assembly illustrated in the drawings, 5 there are two diametrically opposite dogs 41^a, two diametrically opposite dogs 41^b, and two diametrically opposite dogs 41^c.

The invention includes means for yieldingly urging the pivoted core gripping dogs inwardly to 0 engage or cooperate with the core. Notches 48 are provided in the outer ends of the dogs 41 to intersect the opening passing the pins 42. Helical torsional springs 49 surround the pins 42 within the notches 48. Each spring 49 has an end bearing against a shoulder 37 and an end bearing against the outer wall of a notch 48, and is under a torsional strain so as to normally yieldingly urge the core gripping dog downwardly and outwardly into the core passing opening 38. The 15 notches 48 carrying the springs 49 are spaced between the opposite vertical sides of the dogs 41 so that the sides of the dogs are operable to bear against the side walls of the slots 39. Means is provided for supporting the pivoted end portions 20 of the dogs 41 when the dogs are carrying the core. Each dog 41 is provided with a flat face or shoulder 50 operable to bear against the lower end 51 of a slot 39, and is provided with a shoulder 52 for bearing upwardly against the upper wall 53 25 of a slot 40. The bearing shoulders 50 and 52 of the dogs 41 are spaced substantial distances apart around the axis of pivotal movement of the dogs so that their engagement with the seats 51 and 30 53 dependably holds the dogs against turning 35 movement when they are in the extended or down positions supporting the core. The body of the core catcher 13 has limited longitudinal movement in the recess 25 between the shoulder 28 and the upper wall of the recess 33. Cam faces 40 54 are provided on the protruding outer parts of the dogs 41 that are adapted to cooperate with the inclined shoulder 27 upon upward movement 45 of the bit head relative to the core catcher to urge or pivot the dogs inwardly and downwardly in the opening 38. This camming engagement of the faces 54 with the shoulder 27 aids the action of the springs 49 and insures the positive inward pivoting of the dogs. The core catcher 13 forms the subject of our divisional application for 50 Letters Patent entitled "Core catcher" Serial Number 709,461, filed February 2, 1934.

The present invention provides means for circulating the drilling fluid or rotary mud directly from the annular space S between the barrels 10 and 12 through passages in the bit head body 20 to discharge at the forward faces of the cutting blades. The rotary mud or circulation fluid is pumped downwardly through the drilling string and flows downwardly through the annular space 60 S between the two barrels. Downwardly and outwardly inclined ports 60 are provided in the enlargement 29 of the inner barrel to carry the fluid from the space S to an annular groove or channel 61 in the bit head body 20. The annular channel 61 is provided to distribute the fluid to vertical discharge passages 62 in the bit head body 20. The passages 62 discharge downwardly at the lower end of the bit head body 20 immediately in front of the cutting blades of the head. The flow 70 of the circulation fluid does not in any way interfere with the freedom of the inner barrel 12 and the core catcher 13 to remain stationary relative to the core during drilling. The fluid that may possibly leak from the ports 60 and channel 61 to 75 the recess 25 merely flushes the core catcher,

thereby maintaining its freedom of movement. The discharge ports 62 are preferably rectangular in horizontal cross-section and their outer sides are closed by replaceable plates 63.

The valve 14 is provided on the upper end of the inner barrel 12 to permit the escape of liquid from the barrel as the core enters the barrel and to prevent the circulation fluid from passing downwardly into the upper end of the inner barrel. The valve assembly 14 is removable from the 10 barrel 12 to permit the attachment of the device fully described and claimed in our co-pending application Serial Number 684,019, filed on an even date herewith, entitled Pressure head for core barrels. It is a feature of the invention 15 that the valve 14 is removably attached to the upper end of the inner barrel 12 without the employment of screw threads. The valve 14 includes a disc 70 adapted to removably fit in the upper end portion of the barrel. The disc 70 is provided with a central vertical opening 71 which carries a valve seat 72. A ball valve 73 is operable to cooperate with the seat 72 to prevent the down flow of fluid through the opening 71. A 20 perforated cage 74 carries the valve 73. A plurality of circumferentially spaced lugs 75 is provided on the periphery of the disc 70 and are adapted to be passed into vertical slots 76 in the upper end of the inner barrel 12. In the preferred 25 form of the invention illustrated in the drawings, an enlarged annular member 78 is welded on the upper end of the inner barrel 12, and the slots 76 are provided in this member. The slots 76 are adapted to readily pass the lugs 75 and have lateral notches 79 at their lower ends for receiving the lugs 75. The disc 70 is adapted to be inserted in the member 78 so that the lugs 75 pass 30 downwardly through the slots 76. The disc 70 may then be turned to position the lugs 75 in the notches 78. 35

A latch 80 is pivoted on the upper end of the disc 70 and is adapted to be swung downwardly to occupy a slot 76 and thereby prevent the lugs 75 from leaving the notches 79 so that the disc 70 cannot be turned or displaced. The latch 80 45 is sufficiently long and of sufficient thickness so that it cannot swing out of the slots 76 when the inner barrel is within the outer barrel 10. Vertical reinforcing ribs 81 are provided on the portions of the member 78 provided with the notches 50 79. The ribs 81 extend downwardly below the lower end of the member 78 to reinforce the weld connecting the member with the barrel 12. The lower portions 82 of the ribs 81 are increased in thickness to engage the interior of the outer barrel 10 in the event that the inner barrel sways, thereby eliminating the possibility of the member 78 becoming bent between its slots 76. Radial 55 guide plates or webs 84 are provided on the upper end of the disc 70 and are attached to the valve cage 74. The webs 84 form effective guides on the inner barrel 12. 60

During operation, the drill is rotated on the lower end of a string of drill pipe in the usual manner. Circulation fluid is continuously 65 pumped down through the drilling string and discharges from the lower ends of the ports 62 at the forward faces of the cutting blades. The pilot portions 21 of the cutting blades make a comparatively narrow annular channel in the 70 formation cutting a core which is received by the opening 24 and the inner barrel 12. The reaming portions 22 of the blades enlarge the bore and cut it to size as the drilling continues. The comparatively narrow channel formed by the pilot 75

portions 21 of the cutting blades does not permit the major flow of the circulation fluid to directly wash against the core. As the core enters the drill, the gripping dogs 41 are pivoted upwardly 5 into the slots 39. The springs 49 acting on the dogs 41 yieldingly urge the dogs against the core so that the core catcher body is held against rotation. As described above, the core catcher is freely rotatably mounted in the recess 25 and 10 therefore may be held against rotation during the drilling operation. As the core catcher does not rotate, the gripping dogs 41 do not cut or tear up the core and are not seriously worn through contact with the core. Further, as the 15 core catcher may not rotate with respect to the core, there may be only slight clearance between the wall of the opening 38 and dogs 41 with the core so that there is little danger of the core slipping back through the core catcher when 20 the drill is removed from the well. The core while being formed, is free to pass upwardly into the inner barrel 12 and its frictional engagement with the inner barrel may hold the inner barrel against turning. The inner barrel 12 is light in 25 weight, and is freely rotatable at its lower end within the bit head 11 so that its contact with the core results in it being held against turning. As the walls of the inner barrel 12 are very thin, the drill may be proportioned to cut and obtain 30 a core of maximum diameter. The valve 73 may open during the drilling to permit the escape of fluid that may be trapped in the upper end of the inner barrel 12. The valve 73 is normally closed to prevent the circulation fluid from flowing 35 downwardly into the inner barrel 12. The projecting enlarged portions 82 of the ribs 81 operate to prevent excessive swaying of the inner barrel without in any way interfering with the downward flow of the circulation fluid between the 40 barrels 10 and 12. The latch 80 locks the lugs in the notches 79 so that the disc 70 cannot become displaced from the inner barrel 12.

The rotatable mounting of the inner barrel 12 and the rotatable mounting of the core catcher 45 13 are simple and do not complicate the construction as the circulation fluid is diverted through the ports 60 to the bit head channel 61 without necessitating the provision of ports etc., in the 50 mountings. The valve 14 is readily removable from the inner barrel at the derrick to permit the connection of the pressure head with the barrel. The core catcher 13 is particularly effective as its dogs 41 are operable to catch and support any kind of core. The short dogs 41^a are 55 adapted to dependably grip and carry cores of hard earth formations, while the medium dogs 41^b are adapted to retain the cores of softer for-

mations. The longest dogs 41^c prevent broken cores from sifting or passing out of the inner barrel. The rivets 44 connect the rings 35 and 36 and the core barrel body and operate to prevent slipping of the dog carrying pins 42. The dogs 41 are easily replaced in the manner described above. The means for supporting the dogs 41 in the body of the core catcher is important, as it provides for the dependable bracing and supporting of the dogs when they are carrying a core. The spaced bearing faces 50 and 52 of the dogs are operable to cooperate with the shoulders on the core catcher body when the dogs are in their down position to positively limit further downward pivoting. The cam faces 1 54 of the core gripping dogs cooperate with the shoulder 27 of the bithead body to cause the positive downward pivoting of the gripping dogs when the drill is raised. The core drill provided by the present invention is particularly simple 2 and inexpensive of construction and is operable to effectively and dependably obtain cores of 2 large diameters.

Having described only a typical form and application of our invention, we do not wish to be 2 limited or restricted to the specific form and application herein described, but is to be considered as including any variations or modifications that may appear to those skilled in the art or fall 3 within the scope of the following claims.

Having described our invention, we claim:

1. In a core drill, an outer barrel, a bit head on the lower end of the outer barrel, an inner barrel within the outer barrel for receiving a core, there being a bayonet slot in the upper end 35 of the inner barrel, a member adapted to be inserted in the upper end of the inner barrel, a projection on the member adapted to cooperate with the slot to detachably connect the member to the inner barrel, a latch pivoted on the member and adapted to extend into the slot to prevent displacement of the projection, the latch being proportioned and related to the outer barrel so that the outer barrel prevents it from leaving the slot, there being a passage in the member, and a valve for controlling the flow 40 through the passage.

2. An assembly for arrangement in the outer barrel of a core drill including a tubular thin-walled body having spaced bayonet slots in its 50 upper end portion, reinforcing ribs on said portion at the slots, a valve carrier for arrangement on the upper end of the body, lugs on the carrier for cooperating with the slots, and releasable means locking the lugs in the slots.

JOHN H. HOWARD.
ALFRED C. CATLAND.
